UNITED STATES PATENT OFFICE.

FRANK McFADDEN, OF VANATTA, OHIO.

FIRE-ALARM.

SPECIFICATION forming part of Letters Patent No. 756,686, dated April 5, 1904.

Application filed April 16, 1903. Serial No. 152,966. (No model.)

To all whom it may concern:

Be it known that I, FRANK McFADDEN, a citizen of the United States, residing at Vanatta, in the county of Licking and State of 5 Ohio, have invented certain new and useful Improvements in Gas-Alarms, of which the following is a specification.

The purpose of this invention is to devise a novel mechanism for sounding an alarm in the 10 event of the flame of a gas light or stove becoming extinguished from any cause, thereby giving warning and preventing casualties resulting from escaping gas, such as explosion and asphyxiation.

15 The alarm comprises a thermal device, a gong or like audible signal, and a train of gearing for escaping and sounding of the alarm when released by contraction of the thermal device incident to cooling of same after the flame or 20 light has been extinguished.

For a full description of the invention and the merits thereof and also to acquire a knowledge of the details of construction of the means for effecting the result reference 25 is to be had to the following description and drawings hereto attached.

While the essential and characteristic features of the invention are susceptible of modification, still the preferred embodiment of the 30 invention is illustrated in the accompanying drawings, in which—

Figure 1 is a perspective view showing the alarm used in connection with a gas-light. Fig. 2 is a front view, the thermal device being 35 in section and a part of the frame of the alarm mechanism being broken away. Fig. 3 is a sectional view at the line XX of Fig. 2. Fig. 4 is a top plan view. Fig. 5 is a detail perspective view of the detent.

40 Corresponding and like parts are referred to in the following description and indicated in all the views of the drawings by the same reference characters.

The alarm comprises a thermal device 1, 45 gong 2, alarm mechanism 3, and detent 4, the latter having positive connection with the thermal device and automatically actuated thereby for releasing the alarm mechanism when the flame becomes extinguished. The 50 thermal device within the purview of the in-

vention may be of any construction readily affected by changes in temperature so as to effect automatic release of the alarm mechanism whereby a warning is sounded. In the preferable construction the thermal device 55 comprises pan or cup 5 and a diaphragm 6, the latter closing the open side of the pan or cup and secured at its edges to the rim of said pan or cup and forming a tight joint therewith, so as to confine the air, this being essential in order to secure the effective and successful operation of the device. The diaphragm 6 may be of any construction so as to readily move according to the pressure of the confined air.

60 The detent 4 consists of a rod or bar having adjustable connection at its lower end with a socket 7, applied centrally of the diaphragm and adapted to make screw-thread connection with said detent to admit of adjusting same 65 to release the alarm mechanism within a slight variation of a given temperature.

70 The alarm mechanism comprises frame 8 and a train of gearing of any approved construction and comprising escape-wheel 9, with which detent 4 co-operates to hold the alarm mechanism out of action when the lamp or stove is burning. The alarm mechanism is operated by a spring in the usual way, said spring being adapted to be wound by means 75 of key 10 in the well-known manner. The hammer 11 is adapted to strike against gong 2, and its stem is connected at its upper end to pallet-lever 12, which co-operates with escape-wheel 9 when the alarm mechanism is released.

75 The working parts are secured to a suitable base 13 and may be housed in any desired way for protection. When using the alarm, it is placed so that the thermal device comes within the heating zone of the light or flame, whereby the air confined in the chamber of the pan or cup may be expanded and force detent 80 upward into the path of one of the teeth of the escape-wheel 9, after which the alarm mechanism is wound. Should the heat fall below 85 a given degree, the thermal device will proportionately cool, and the confined air diminishing in pressure will permit the detent to lower and release the escape-wheel and sound 90 95 100

the alarm. In the event of the heat regaining the given degree before the alarm mechanism is run down the detent will again be projected so as to engage with a tooth of the escape-wheel and restrain the alarm mechanism until the heat again falls below the predetermined degree. In the event of the light or flame becoming extinguished the thermal device cooling quickly will effect a sounding 10 of the alarm, thereby apprising any one within hearing of the alarm that the light or flame has gone out, so that the gas may be turned off, thereby preventing the fatalities frequently attributable to escaping gas.

15 Having thus described the invention, what is claimed as new is—

In combination, a pan or cup, a diaphragm closing the open side thereof and provided at

a central point with a threaded extension, an alarm mechanism comprising an escape-wheel, 20 a gong, a hammer for sounding an alarm upon said gong and connected with the pallet-lever of the alarm mechanism, and a detent having screw-thread connection with the extension of said diaphragm and adapted to extend 25 across the path of the teeth of said escape-wheel to hold the alarm mechanism in restraint under normal conditions, substantially as set forth.

In testimony whereof I affix my signature in 30 presence of two witnesses.

FRANK McFADDEN. [L. S.]
